UNITED STATES PATENT OFFICE.

EVERT LAUTENBACH, OF CHICAGO, ILLINOIS.

SKIRT-LIFTER.

SPECIFICATION forming part of Letters Patent No. 726,951, dated May 5, 1903.

Application filed August 16, 1902. Serial No. 119,832. (No model.)

To all whom it may concern:

Be it known that I, EVERETT LAUTENBACH, a citizen of the United States, residing at Chicago, in the county of Cook and State of Illinois, have invented certain new and useful Improvements in Skirt-Lifters; and I do hereby declare the following to be a full, clear, and exact description of the invention, such as will enable others skilled in the art to 5 which it appertains to make and use the same, reference being had to the accompanying drawings, and to the letters and figures of reference marked thereon, which form a part of this specification.

15 My invention relates to improvements in skirt-lifters, and has for its object to provide a simple and convenient device for raising or lowering the skirt and for retaining it in the desired position.

20 A further object is to provide simple and efficient means for holding a tape or strap at place in a loop and for sustaining pull thereon.

In the accompanying drawings, Figure 1 is 25 a plan view of the device. Fig. 2 is an enlarged section on the line 2-2 of Fig. 1. Fig. 3 is a side elevation of a skirt, showing my device thereon in dotted lines.

Referring specifically to the drawings, 4 30 indicates two pieces of tape sewed together at their edges and also stitched across, as indicated at 4^a, forming a series of pockets 4^b. In each pocket a small thin metal plate 5 is held for a purpose to be hereinafter stated.

35 A ring 6 is sewed at one end of the tape, and at the other end a retaining-bead 7 is formed. A number of spreading pieces of tape 6^a are

sewed at one end to the ring 6 and at the other end to the inside of the skirt S. The tape 4 passes through a strap-loop 8, attached to a 40 plate 8^a, the projecting edges of which have perforations 8^b for sewing the plate to the skirt-band S. The strap-loop and plate are preferably formed of metal.

To raise the skirt, the tape 4 is drawn up 45 through the loop 8, and to make it fast, and thus hold the skirt up, the tape is bent over the upper edge of the loop, as shown in Fig. 3. The tape in this position will not pull down through the loop, because of the inflexibility of the metal plate 5, engaging the top edge of the loop at the bight of the tape. To lower the skirt, it is necessary only to straighten the tape 4 to bring the plates fair or in line with the loop, when it will readily 50 draw down through. The free end of the tape may be tucked in under the skirt-band to keep the tape bent at the loop.

What I claim as new, and desire to secure by Letters Patent, is—

60 The combination with a strap formed of a series of inflexible sections flexibly joined together, of a loop through which the strap passes and over which it is bent at one of the joints, whereby the strap is held by engagement of an inflexible section with the loop, substantially as described.

In testimony whereof I affix my signature in presence of two witnesses.

EVERT LAUTENBACH.
